WRITING IMPLEMENT CONTAINER

Cecil B. Woofter, Newton, Iowa, assignor to
The Vernon Company

Filed June 24, 1971, Ser. No. 156,590

Term of patent 14 years

Int. Cl. D19—02

U.S. Cl. D74—5

FIG. 1.

FIG. 2.

FIG. 4.

FIG. 3.

FIG. 5.

FIG. 1 is a perspective view of a writing implement container embodying my new design;

FIG. 2 is a side elevational view of the back panel of FIG. 1;

FIG. 3 is an elevational view of the left side panel of FIG. 1;

FIG. 4 is a top plan view showing the grooves on the interior bottom surface; and

FIG. 5 is a bottom plan view thereof.

I claim:

The ornamental design for a writing implement container, substantially as shown.
